UNITED STATES PATENT OFFICE.

JOSEPH BLEFELD, OF PHILADELPHIA, PENNSYLVANIA, ASSIGNOR TO SOLOMON BLEFELD, OF PHILADELPHIA, PENNSYLVANIA.

SCHOLAR'S COMPANION.

1,117,967.

Specification of Letters Patent. Patented Nov. 24, 1914.

Application filed May 24, 1913. Serial No. 769,569.

To all whom it may concern:

Be it known that I, JOSEPH BLEFELD, a citizen of the United States, residing at Philadelphia, in the county of Philadelphia and State of Pennsylvania, have invented 5 certain new and useful Improvements in Scholars' Companions, of which the following is a specification.

My invention relates to improvements in scholars' companions, the object of the invention being to provide a neat and attractive device of this character which permits the ready transportation of books and papers, together with pencils, pens, erasers, etc.

15 A further object is to provide an improved construction of article holder which can be manufactured and sold at a reasonably low price, and which will most efficiently perform the functions for which it is intended.

20 With these and other objects in view, the invention consists in certain novel features of construction and combinations and arrangements of parts as will be more fully hereinafter described and pointed out in the 25 claims.

In the accompanying drawings: Figure 1 is a view in side elevation illustrating my improvements. Fig. 2 is a view in section on the line 2—2 of Fig. 1. Fig. 3 is a 30 fragmentary view in vertical longitudinal section on the line 3—3 of Fig. 2. Fig. 4 is a view in section on the line 4—4 of Fig. 3.

1 represents a cylindrical receptacle having a closed end 2 and in which a drawer 3 is mounted to slide. This drawer 3 has an 35 end 4 corresponding in shape to the closed end 2, so that when the drawer is in position in the receptacle, it will be alike at both ends except that a handle 5 is provided on the 40 drawer to facilitate its movement. The drawer 3 is semi-circular in cross section as shown most clearly in Fig. 4, but the inner end 6 and outer end 4 are complete circles in cross section as is also a partition 7 which 45 divides the drawer into two compartments.

The ends 4 and 6 and partition 7 fit the cylindrical bore of casing 1, but any turning movement of the drawer is prevented by a cross pin 8 which extends through the casing 50 and over the edges of the drawer 3 as clearly shown in Figs. 3 and 4. This pin 8 also limits the outward movement of the drawer as it is engaged by the end 6 when the drawer is pulled outwardly.

55 Metal bands 9 are secured around casing 1

and are provided on the upper edge of the casing with bearings 10 for the ends of a bail 11 on which a handle 12 is mounted.

Links 13 are supported by the bands 9 below the casing 1 and through these links, 60 short sections of strap 14 are positioned and secured at their ends by rivets 15 to longer straps 16. These straps 16 at their ends are secured to horizontal bars 17, and a single strap 18 located midway between the straps 65 16 is secured by rivets 19 to the bars 17, and is adapted to be positioned around books 20 or other similar articles as clearly shown.

Strap 18 has a buckle 21, so that it may be adjusted to properly clamp the articles. 70 The bars 17 may be of fiber or some other relatively strong material, and when positioned at opposite sides of the articles to be clamped, will maintain the several straps in parallelism and afford a relatively wide gripping surface to bind the articles together. 75 By the arrangement of short straps 14, and longer straps 16, the straps are permitted a certain amount of movement in the loops 13 without injuring the article clamped by the 80 straps.

Various slight changes might be made in the general form and arrangement of parts described without departing from my invention, and hence I do not limit myself to the 85 precise details set forth, but consider myself at liberty to make such changes and alterations as fairly fall within the spirit and scope of the appended claims.

Having thus described my invention, what 90 I claim as new and desire to secure by Letters Patent is:

1. A device of the character described, comprising a cylindrical casing, a drawer mounted to slide in the casing, said drawer 95 of general semi-cylindrical form, and a pin projected across the casing and in proximity to the upper edges of the drawer, whereby said pin prevents rotary movement of the drawer in the casing, substantially as described.

2. A device of the character described, comprising a cylindrical casing, a drawer mounted to slide in the casing, said drawer 105 of general semi-cylindrical form, a pin projected across the casing and in proximity to the upper edges of the drawer, whereby said pin prevents rotary movement of the drawer in the casing, and circular partitions constituting a part of the drawer fitting within 110

the cylindrical casing and between two of which said pin is positioned, whereby the sliding movement of the drawer in the casing is limited by the engagement of one of said partitions with the pin, substantially as described.

In testimony whereof I have signed my

name to this specification in the presence of two subscribing witnesses.

JOSEPH BLEFIELD.
